UNITED STATES PATENT OFFICE.

JOHN S. YOUNG, OF SAN DIEGO, CALIFORNIA, ASSIGNOR OF ONE-FOURTH TO MAUDE L. YOUNG AND ONE-HALF TO LANE D. WEBBER, BOTH OF SAN DIEGO, CALIFORNIA.

FOLDING BED.

Application filed September 7, 1922. Serial No. 586,638.

My invention relates to beds more particularly to folding closet beds and the objects of my invention are: first, to provide a bed of this class which can be easily folded up, positioned on its end and moved into a closet, against the wall or the like; second, to provide a bed of this class which can be easily shifted to an upright position and retained in said position by its own weight; third, to provide a bed of this class in which the rail at the foot end of the bed can be folded down against the mattress to hold the mattress in position on the springs while in an upright position; fourth, to provide a bed of this class in which the legs at the foot end of the bed can be folded up as the bed is shifted into an upright out of the way position; fifth, to provide an attachment for beds which can be applied to most beds now in use for positioning the same in an upright position so they can be easily moved about and concealed in a closet or easily moved from one room to another; sixth, to provide a novelly constructed bed structure of this class and seventh, to provide a bed of this class which is very simple and economical of construction, durable, efficient and which will not readily deteriorate or get out of order.

With these and other objects in view as will appear hereinafter my invention consists of certain novel features of construction, combination and arrangement of parts and portions as will be hereinafter described in detail and particularly set forth in the appended claim reference being had to the accompanying drawings and to the characters of reference thereon which form a part of this application in which:

Figure 1 is a plan view of my bed structure with the mattress partially broken away to facilitate the illustration; Fig. 2 is a side elevational view thereof showing by dotted lines the rail at the foot end of the bed folded downwardly against the mattress and clamped in position, and also showing by dotted lines the bed positioned in an upright position with the rail and legs at the foot end folded downwardly; Fig. 3 is a fragmentary end elevational view taken from the foot end of the bed showing the rail bent downwardly and Fig. 4 is a plan view of a slightly modified form of construction of my bed showing the rail and legs at the head end wider than that of the conventional bed, as

shown in Fig. 1, and showing slightly modified means for supporting the bed spring.

Like characters of reference refer to similar parts and portions throughout the several views of the drawings.

The head end support 1, bracket members 2, legs 3, journal members 4, tie members 5, foot end supporting members 6, legs 7, pins 8, latch members 9, retaining members 10, pins 11, foot end rail 12, spring supporting rails 13, pivot bolts 14, bed spring 15, bolts 16, mattress 17, hooks 18, springs 19 and the weights 20 constitute the principal parts and portions of my bed structure in its preferred form.

The head end support 1 of the bed structure is of the conventional type and is provided at each leg portion with an outwardly extending bracket member 2 to take the place of the slotted member in the head end member of the conventional bed. Positioned in front of and slightly offset from the leg portions of the head end support 1 are the legs 3 provided at their upper ends with journal members 4 which journal members are secured to and spaced from the bracket member 2 by tie members 5. The foot end support consists of foot end supporting members 6, tied together laterally by a tie member 6^a. Said supporting members 6 are provided with downwardly extending lug portions 6^b to which are hinged the legs 7 by the pins 8 which extend through said members. Resilient latch members 9 are secured to the legs 7 which tend to keep the legs 7 from collapsing when the bed is lowered and also tend to keep the legs folded up when the bed is in an upright position. Said foot end supporting members 6 are also provided with a central longitudinal hole 6^c to receive the retaining members 10 which are reciprocally mounted therein. Said retaining members 10 are provided with slots 10^a near their lower end which are adapted to guide and limit the upward movement of the retaining members 10 by reason of the pins 11, provided in the supporting members 6, engaging the lower end of the slotted portion of said member. Said retaining members are also provided with slots 10^b at their upper portion to receive corresponding lugs 12^a provided at the lower portions of the foot end rail 12 which is pivotally connected to the members 10 by pins 12^b extending through the lug of said foot end rail member and the slotted 105

portion of the retaining members 10. The reciprocal mounting of the retaining members 10 permits the foot end rail 12 to be at all times connected with the foot end supports 6, said members 10 serving as guides for shifting the foot end rail to a vertical position for inserting the lower ends of the same into the members 6. Said members 10 serve also as a raised pivotal mounting and retaining means when folding the rail downwardly against the mattress when securing the latter in position on the frame. The supporting members 6 are also provided with laterally extending lugs 6^a to receive and support the spring supporting rails 13 which are preferably angle shaped similarly to the conventional supporting rails but are preferably permanently secured to the foot end supporting members 6 by bolts 6^b. The free ends of said supporting rails 13 are pivotally mounted in the journal members 4 by pivot bolts 14. Said supporting rails 13 are adapted to receive and support the bed spring 15, the frame 15^a of which spring 15 is preferably permanently secured to the supporting rails 13 by bolts 16. The mattress 17 is supported on the spring 15 in the conventional manner but is secured to said spring by the foot end rail 12 which is adapted to fold downwardly over one end of the mattress and is secured in said position by hooks 18 pivotally mounted on the supporting rail 13 and adapted to engage lugs 12^c on the foot end rail 12. When the bed is folded up and shifted in a vertical position as shown by dotted lines in Fig. 2 of the drawings the bed is held in said position by its own weight and by reason of the position of its pivotal mounting. However, in order to facilitate the raising of the bed to its vertical position I have provided a spring 19 mounted at one end to the head end of the frame of the spring 15 and at its other end to the legs 3, which spring 19 also serves to hold the bed in an upright position. To further assist in balancing the bed and holding it in an upright position I have provided a weight 20 at the head end of the spring 15.

In Figure 4 of the drawings I have shown a slightly modified form of construction in which I have provided a special head end support 21 which is slightly wider than the support shown in the preferred form in Fig. 1 of the drawings. The tie members 5 in the modified form of construction are secured in line with the leg portions of the head end support without necessitating the use of an additional offset bracket. Also in the modified form of construction the supporting rails

are eliminated and the spring is directly pivoted on the journal members 4 as shown in Fig. 4 of the drawings.

Though I have shown and described a particular construction, combination and arrangement of parts and portions and a certain modification thereof I do not wish to be limited to this particular construction, combination and arrangement nor to the modification but desire to include in the scope of my invention the construction, combination and arrangement substantially as set forth in the appended claim.

It is obvious that I have provided a bed which may be easily folded up, positioned on its end and moved into a closet, against the wall or the like; which can be easily shifted to an upright position and retained in said position by its own weight; that the rail at the foot end of the bed can be folded down against the mattress to hold the same in position on the springs while shifted to an upright position; in which the legs at the foot end of the bed can be folded up and out of the way; that I have provided an attachment for beds which can be applied to most beds now in use for shifting the same in an upright position so that it can be easily moved about from one room to another and concealed in a closet; that I have provided a novelly constructed bed of this class and that I have provided a bed of this class which is very simple and economical of construction, durable, efficient and which will not readily deteriorate or get out of order.

Having thus described my invention what I claim as new and desire to secure by Letters Patent is:

In a folding bed, a head-end supporting member provided with leg portions, other backward leg portions in spaced relation with the leg portions of said supporting member and provided with journal portions, a bed spring supporting frame pivotally mounted on one end in the journal portion of said legs and extending backwardly only from said journal member and a bed spring secured to said bed spring supporting frame and extending forwardly and backwardly of said journal portions and a spring member with one end secured to the forward end of said spring frame and its other end secured to the backward leg portions for balancing said spring and frame relatively to said head-end supporting member.

In testimony whereof, I have hereunto set my hand at San Diego, California, this 2nd day of September, 1922.

JOHN S. YOUNG.
